US0D1056129S

(12) **United States Design Patent** (10) **Patent No.:** **US D1,056,129 S**
(45) **Date of Patent:** **** Dec. 31, 2024**

(54) **HAND-HELD ELECTRIC SPRAYER**

(71) Applicant: **Hangzhou Weirran Machinery Co., Ltd**, Hangzhou (CN)

(72) Inventor: **Qunwei Jia**, Hangzhou (CN)

(73) Assignee: **HANGZHOU WEIRAN MACHINERY CO., LTD**, Hangzhou (CN)

(**) Term: **15 Years**

(21) Appl. No.: **29/813,424**

(22) Filed: **Oct. 28, 2021**

(30) **Foreign Application Priority Data**

Sep. 8, 2021 (CN) 202130594712.1

(51) LOC (14) Cl. **23-01**

(52) U.S. Cl.

USPC **D23/226**

(58) **Field of Classification Search**

(57) **CLAIM**

The ornamental design for a hand-held electric sprayer as shown and described.

DESCRIPTION

FIG. 1 is a perspective view of a hand-held electric sprayer showing my new design;

FIG. 2 is a front plan view thereof;

FIG. 3 is a rear plan view thereof;

FIG. 4 is a left-side plan view thereof;

FIG. 5 is a right-side plan view thereof;

FIG. 6 is a bottom plan view thereof;

FIG. 7 is a top plan view thereof;

FIG. 8 is a left-side perspective view of a hand-held electric sprayer according to a second embodiment of my new design;

FIG. 9 is a right-side perspective view thereof; and,

FIG. 10 is a left-side perspective view of a hand-held electric sprayer according to a third embodiment of my new design.

1 Claim, 10 Drawing Sheets
